INDUCTANCE COIL

Original application filed December 20, 1925, Serial No. 78,472. Divided and this application filed April 26, 1927. Serial No. 186,630.

This invention relates to inductance or reactance coils for connection in electrical circuits, and particularly to coils for use in the prevention or elimination of high frequency oscillations in such circuits, for the purpose of eliminating radio interference or for other purposes. This application is a division of my United States patent application Ser. No. 78,472 filed December 20, 1925 for Method and apparatus for prevention of radio interference due to high frequency radiation from complex electrical circuits.

The principal object of the invention covered in this divisional application is to provide a particularly advantageous type of inductance or reactance coil for use in the prevention of high frequency oscillations.

In the elimination of high frequency oscillations in electrical circuits, and particularly in the elimination of such oscillations in the operating circuits of electrical precipitators as described in my above mentioned application, it is of advantage to produce absorption rather than reflection of the high frequency currents. That is to say, it is desirable to absorb the energy of the high frequency oscillation within the coil, rather than to cause such energy to be reflected back into the circuit. The use of ordinary choke coils often causes high voltages to build up ahead of the choke due to reflection phenomena and to the high reactance of the choke. Such high potentials, if superimposed on the low frequency voltage of an electrical precipitator circuit may cause disruptive peak voltages and thus impair the operation of the precipitator.

It is therefore advantageous in such cases to employ a coil having an iron core, as such iron core not only increases the effective resistance due to hysteresis losses but also decreases the inductance due to the iron core acting to a certain extent as a short circuited secondary winding for the choke coil. This latter effect may be enhanced by providing an external rather than internal iron core. By this means therefore the absorption of energy due to the effective resistance of the choke may readily be increased to the desired extent without introducing an excessive

value of inductance. In an ordinary solid iron core coil, however, a capacity exists between the coil and core and high frequency current may therefore flow across such capacity at the ends of the coil and hence through the iron core thus greatly lowering the impedance of the coil at high frequencies. 55

An important object of this invention is to provide an energy absorbing inductance coil, which may be termed an absorber coil, which has a maximum energy absorbing effect by virtue of the provision of an iron core therein, and which at the same time presents a minimum tendency to conduct high frequency current because of the coil-to-core capacity. This object is accomplished by the use of an external iron core composed of a plurality of short sections, each insulated from one another, and each forming a complete short circuited secondary. In a coil of this type the high frequency currents passing by capacity from the coil to any section of the core are substantially prevented from passing along the core due to the interposition of the insulating layers which present high resistance and low capacity. 70 75

In circuits, such as electrical precipitator circuits, it is often desirable to connect inductance coils directly in a transmission line, and a further object of this invention is to provide an inductance coil which is adapted for connection in this manner and is of sufficient mechanical strength to support and transmit the strain or stress existing in such a line due to the weight thereof between supports. A coil of this construction may be termed a strain type inductance coil. When connected in a conducting line or between two conducting members, it forms mechanically an integral part of the line but interposes an electrical inductance of the desired value therein. 80 85

The accompanying drawings illustrate 95 embodiments of my invention and referring thereto.

Fig. 1 is a longitudinal section on line 1-1 in Fig. 2, showing an absorber coil in accordance with my invention. 100

Fig. 2 is a transverse section on line 2—2 in Fig. 1.

Fig. 3 is a longitudinal section of one end of an absorber coil of the strain type.

Fig. 4 is a transverse section on line 4—4 in Fig. 3.

The coil shown in Figs. 1 and 2 consists essentially of a central supporting tube 1 of bakelite or other insulating material around which are wound a sufficient number of turns of wire to form the coil itself, indicated at 2. The winding may be made to have any desired value of inductance. In one case, I have used for example a 2 $\frac{5}{8}$ inch 10 bakelite tube with a 3000 microhenry winding consisting of No. 26 D. C. C. wire. The winding is preferably of the single layer type, instead of multi-layer, as it has been found that multi-layer coils have much higher 15 inter-coil capacity than do single layer coils. A plurality of external iron rings 3 are placed around the winding 2 and are spaced therefrom as by means of strips 4 of bakelite or other insulating material. 20 Rings 3 may be spaced apart in any suitable manner, for example by means of insulating material such as cord 5 wound around between such rings. The entire coil, after construction, should be dipped in varnish and 25 baked.

The absorber may be considered electrical- 30 ly as comprising a 3000 microhenry primary winding, around which are placed a plurality of one-turn short circuited secondary coils, constituted by the iron rings 3 35 extending completely around the coil. The external rings, being made of iron, act also to decrease the reluctance of the external part of the magnetic circuit, and hence increase 40 the magnetic flux, and the sectional construction of this external core acts to reduce the passage of high frequency currents due to internal capacity to the minimum value consistent with fairly close coupling.

The effective resistance of the absorber 45 coil varies approximately with the square of the frequency. The higher transients therefore suffer much greater attenuation than the low frequency pulsating rectified current 50 such as used in electrical precipitator operation. As a result, the losses for the rectified current are reduced to a minimum, while the losses for the undesirable high frequency transients are great. It can be shown that 55 the high frequency resistance of the absorber coil may be many thousands of ohms, while the low frequency resistance for the rectified pulsating current is only a fraction of an ohm.

In any coupled circuit the apparent re- 60 actance of the primary is always changed by the presence of the secondary, and it may be further shown that the effective inductance of the primary is decreased by the current flowing in the secondary circuit. Consider-

ing the relationships existing between effective resistance and inductance in coupled circuits of this type, it is seen that the effect of the current flowing in the secondary is to increase the resistance of the primary 70 circuit, and to decrease its self induction.

It may also be shown that these effects vary directly with the square of the frequency. The low frequencies suffer only slightly from the small change in effective 75 resistance, while for the higher frequencies the effective resistance is greatly increased and the self-inductance is greatly decreased. This increase in resistance and decrease in inductance tend to prevent oscillations and to 80 absorb or dissipate the energy thereof as has already been shown.

As shown in Figs. 3 and 4 the absorber coil may also be constructed with end connecting members for connection at an intermediate point in a conducting line or between two conducting members so as to support and transmit the stress or strain between such conducting members. The coil may in this case comprise as before a central supporting tube 1 of bakelite or other insulating material, an inductance coil 2 wound upon said tube, longitudinal spacing strips 4, iron rings 3 and suitable spacing means 5 such as bakelite rings between said iron rings. An 90 end connecting member 10 is further provided at each end of the coil, each of such connecting members having a hollow cylindrical portion 11 fitting over the end of the bakelite tube and also comprising a projection or lug 12 provided with suitable means such as hole 13 for connection of the conducting line thereto, as shown for example at 14. Each of the end connecting members 10 may be mechanically secured to the bakelite supporting tube by means of metallic pins 15 extending through holes in the cylindrical portion 11 of said conducting member and in the end of the bakelite tubing. Said pins are disposed in different angular positions as shown in Fig. 4, and are of sufficient 100 size and number to support the weight of the conducting line. The central supporting member 1 must also be of sufficient strength to support and transmit the stress due to the weight of the line. The electrical connection between winding 2 and end members 10 may be provided by carrying each end of 105 said winding, as indicated at 17, out through groove 18 in the bakelite tube and through hole 19 in end member 10, and soldering or otherwise securing the end of wire 17 to the end member as at 20. It will be seen that 110 when a coil of this type is connected between two portions of a conducting line it forms 115 mechanically an integral part of the line but interposes a high frequency impedance of the 120 desired value therein.

I claim:

1. An absorber coil comprising a wire in-

duction coil, a plurality of iron rings extending completely around said coil and insulated therefrom, said iron rings being spaced from each other, whereby each of said rings forms a short circuited single turn secondary winding for said induction coil, and all of said iron rings together serving to constitute an external core of low magnetic reluctance for said coil.

10 2. An absorber coil comprising a wire induction coil, an iron core surrounding said coil and insulated therefrom, said iron core being divided longitudinally into a plurality of sections spaced apart from one another, a
15 supporting member of insulating material extending throughout the length of the coil, and connecting members secured mechanically to the ends of said supporting member and connected electrically to the ends of said
20 induction coil.

In testimony whereof I have hereunto subscribed my name this 18th day of April, 1927.

JOHN J. JAKOSKY.
